UNITED STATES PATENT OFFICE

2,144,884

BRUSHLESS SHAVING CREAM

Wolf Kritchevsky, Chicago, Ill., assignor to Rit Products Corporation, Chicago, Ill., a corporation of Illinois

No Drawing. Application December 9, 1932, Serial No. 646,497

15 Claims. (Cl. 167—85)

My invention relates in general to shaving cream. It relates more in particular to the so-called "brushless" shaving cream of the type which does not depend for its action upon the 5 lathering effect of soap.

Preparations employed for shaving have in general a two-fold object. They soften the hair as well as the skin on the face by emulsifying the natural oil present on the skin, and they also 10 lubricate the skin so that the razor will pass over the same easily.

Ordinary shaving soaps are made empirically without any thought to these two functions, but it will be obvious that they must to some extent 15 perform both functions in order to be usable. Those skilled in the art have found that the use of ordinary soaps is not satisfactory and accordingly attempts have been made in the past to produce a shaving cream which would perform both 20 functions required in a more satisfactory manner. These creams are made ordinarily from free fatty acid, usually, stearic acid, and sufficient soap to emulsify the stearic acid in water. Some 25 spermaceti wax or paraffin or other waxes or similar compounds have also been used to make the cream nonvanishing. A mixture of types of substances described emulsified with a relatively 30 large amount of water (sometimes with some glycerin added) are well known. When spread on the face, they leave a substantial deposit of the emulsified stearic acid and waxes which act as a lubricant to prevent the razor from pulling or scratching.

In most of these preparations, a thorough 35 washing of the face is first necessary to remove the natural oils. Otherwise the cream of itself will not adequately soften the beard. As a general rule, these creams are fairly efficient but they are still subject to considerable improvement to 40 remedy their outstanding defects. One difficulty is that in order to function satisfactorily as a lubricant they must have a relatively large amount of fats or waxes in relation to the soap present and this causes them to be too greasy, 45 making it hard to remove them from the face and from the razor. When the amount of wax in proportion to the soap present is decreased so that they can readily be washed from the face or razor, these creams do not lubricate well. Moreover, 50 they all leave something to be desired from the

standpoint of softening the beard. Still another shortcoming is that the emulsions are not sufficiently stable and in cold weather they freeze and the emulsions break. Moreover, they can not be employed satisfactorily when the water employed 5 on the face is cold.

The principal object of my invention is the provision of an improved shaving cream.

Another object is the provision of a shaving cream which obviates all of the difficulties herein- 10 above set out.

Another object is the provision of a shaving cream which will soften the beard even though the beard has been washed only slightly or not at 15 all before the application of the cream.

Other objects and features of the invention will be apparent as the detailed description progresses.

I have found a relatively large class of chemical substances which, as far as I know, have never been employed in brushless shaving creams here- 20 tofore. I have found that these chemical compounds can be employed in creams, the major ingredients of which are fatty acids such as stearic acid and water and the entire product emulsified completely. The emulsion product so 25 produced has very excellent wetting properties in that it tends to soften the beard to a much greater extent than any of the shaving creams heretofore employed. It has a great advantage in being readily washed from the razor, while the re- 30 mainder left on the face after shaving is as readily removed from the face by washing. The product also can be made of such consistency that while it may be freely washed from the razor it will not possess the undesirable property of falling 35 from the razor during shaving. It will be understood that the wetting properties heretofore referred to cause the cream as a whole to wet through the greasy layer on the skin and base of the beard when it is put on the face, thereby 40 forming an intimate contact of the water phase of the cream and skin at the base of the beard so that the softening action is the same or better than that employed by using a soap and brush.

The class of compounds which I have discovered 45 has a well balanced ratio of oleophilic and hydrophilic properties; that is to say the polar and non-polar groupings are present in the molecule in a way that causes the composition as a whole to have both water wetting and oil wetting proper- 50

ties. These compounds, therefore, while having a marked hydrophilic character making them readily miscible or soluble in water, also have oily properties which give them excellent lubricating value during shaving. The combination of hydrophilic and oleophilic properties enables the compound as a whole to penetrate through the greasy layer on the skin, carrying the cream as a whole with it and at the same time enabling the user to remove all the deposits remaining after shaving with water.

Substances of the kinds set out are numerous and of widely differing chemical composition. They all possess these factors in common, however, that they all possess both oleophilic and hydrophilic groupings and all of them serve to decrease the surface tension of water. It will be understood, therefore, that, whenever such substances are mentioned in the claims, they must possess these characteristics.

The oleophilic or non-polar part of the molecule is formed by a hydrocarbon chain of not less than eight carbon atoms. This chain may be in the form of a long chain alkyl group or groups; it may be in the form of aralkyl groups or radicals of long chain fatty acids or long chain alcohols. The hydrophilic part of the molecule consists of a group having a definite attraction for water, such as a number of hydroxy groups or an inorganic acidic group such as a sulphuric acid radical, phosphoric acid radical, esters of such acids as short chain organic chemicals like ethionic acid or esters with polyhydric alcohols like glycol mono-sulphuric acid, etc. The hydrophilic group is connected with the oleophilic or non-polar group either directly as in the case of sulphonic acid or phosphonic acid derivatives of aliphatic hydrocarbons. The compounds may also be in the form of esters of long chain aliphatic alcohols, such as sulphuric esters of alcohols or phosphoric esters of alcohols. The compounds which I employ may also be of a type wherein the oleophilic and hydrophilic groups are interconnected through the residue of a carboxyl group. Thus, for example, on one side of the residue of a carboxyl group there may be a long chain aliphatic hydrocarbon radical such as a higher fatty acid radical and on the other side there may be an acid group or an acid group joined thereto through an aliphatic group such as an ethionic acid radical, or through an ester of a polyhydric alcohol with a strong acid as, for example, glycerin mono-sulphonic acid esterified with a higher fatty acid; or the hydrophilic group may comprise an amine group which may be substituted in the same way as the carboxy radical. The free valences in the —CO— group may be substituted by a monovalent or a polyvalent alcohol radical, by an NH₂ group or an organic amine radical, and a hydrophilic group may be linked to an oleophilic group such as in the sulphonated oils or other derivatives of that type.

In order to teach those skilled in the art the full scope of my invention, I shall name a few representatives of the different classes of compounds indicated. As a sulphonic acid derivative, I wish to cite the cetyl sulphonic acid as described by Reyhler in the Kolloidal Zeitschrift, volume 12, page 277. As another one of this kind, I wish to mention the compound C₁₆H₃₃CHOH—CH₂SO₃Na as mentioned in British Patent 358,583. As an ester of a long chain alcohol, I wish to mention sulphuric acid ester

of lauryl alcohol or oleyl alcohol or cetyl alcohol.

As derivatives of fatty acids, I wish to mention sulphonated castor oil, butyl sulpholeic acid and similar derivatives as disclosed in United States Patents 1,822,977, 1,822,978 and 1,822,979, or the sulphonated mono-oleyl ethylene glycol as disclosed in French Patent 721,340, or the fatty acid derivatives of ethane sulphonic acid as described in United States Patent 1,881,172 or compounds like lecithin.

There are still other compounds which may be referred to briefly, such as sulphonated oleyl amide; compounds of amides of fatty acids in which the amide group is substituted with ethionic acid or other similar derivatives. The main feature is that all of these compounds mentioned as well as all others of the class are excellent emulsifying agents; they are first class wetting agents due to their prominent hydrophilic groups and excellent lubricating agents due to their oleophilic groups.

The creams consist for the most part of a fatty body like the stearic acid or any other solid fatty acid like palmitic acid, etc., with or without a solid fat like hydrogenated fats, lard, waxes, etc. The quantity may range from 5 to 30% depending upon the hardness of the particular vehicle. A certain proportion of soap may or may not be used, ranging from 2 to 10%, or may be omitted. The emulsifying and wetting agent required may range from about ½ to 5% or more. Perfumes and other antiseptic agents may be used in a small percentage as required. The water content preferably ranges between 50 and 80%. The resulting product is a cream of whatever consistency may be desired; a cream which is stable, which when put on the face immediately penetrates the grease layer and spreads until a very thin layer is obtained and which washes off very easily with water by dissolving or dispersing in that water solution; a cream which will not thin out on the face and fall off the razor during shaving.

For the sake of clarity, I shall give a few examples of the composition of my improved cream:

	Per cent
1. Stearic acid	20
Soap	5
Butyl ester of sulphonated oleic acid	3
Carbolic acid	0.1
Perfume	0.5
Water	71.4

In compounding the ingredients, the water is heated and the soap (if used) dissolved in it. Then the melted stearic acid is run into the water solution in a thin stream and the whole agitated until a heavy emulsion is formed. The emulsifying agent is then added and the surface tension immediately breaks and the whole composition thins out almost like water. It is stirred and cooled until it reaches the temperature of 40° C., then the perfume and antiseptic are added.

	Per cent
2. Stearic acid	25
Soap	2
Glycerin	2
Sodium salt of the sulphuric acid ester of lauryl alcohol known as Gardinol	70
W. A.	1
Carbolic acid	0.1
Perfume	0.5
Water	69.4

Technique same as above. The glycerine may be added with the water or later if desired.

	Per cent
3. Stearic acid	20
5. Soap	2.5
Caustic potash	1
Sulphonated castor oil	2
Carbolic acid	0.1
10. Perfume	0.5
Water	73.9
	Per cent
4. Palmitic acid	20
15. Tri-ethanol amine	5
Avirol 142 (sodium salt of cetyl alcohol ester of sulphuric acid)	5
Carbolic acid	0.1
Perfume	0.5
Water	68.9
20. Menthol	.5

Obviously these examples are by no means exhaustive and by no means cover the ground, yet when interpreted in the spirit of my disclosure are sufficient and will teach one experienced in the art how to practice my invention and obtain practical results.

In my disclosure I do not wish to limit myself either to proportions or to chemical procedure. In fact, substantially any composition of matter of this kind may be used as long as it contains a proper vehicle. Such vehicle may be stearic acid or other fatty acid, vegetable fat or mineral fat with or without paraffin or any other fat or wax, like carnauba, synthetic wax like Rigolan wax, and an emulsifying agent with high wetting power that has both oleophilic and hydrophilic groups of the nature described and performing the function indicated falls within the limit of my disclosure.

40. The term "soluble" is used in claims in a broad sense to include the characteristics of both molecular and colloidal solubility in water.

45. The term "chemical substance" when used in the claims is not to be construed to include soaps which are the metal and alkali metal salts of the higher fatty acids, such as, for example, sodium or potassium stearate, palmitate, oleate, etc.

50. What I claim as new and desire to protect by Letters Patent of the United States is:

1. A brushless shaving cream comprising a plastic emulsion of oleaginous material and aqueous material and having included therein a proportion of a chemical compound having oleophilic and hydrophilic groups in the molecule, the oleophilic group comprising a hydrocarbon group containing at least eight carbon atoms, said chemical compound having good wetting and lubricating properties and being miscible with water and having the properties of penetrating through the natural greasy layer on the skin and facilitating the softening of the hair when applied to the skin.

2. The product of claim 1 wherein the oleaginous material is a normally solid fatty acid.

65. 3. A brushless shaving cream comprising a plastic emulsion of oleaginous material having a terminal carboxy group, water, a chemical compound having oleophilic and hydrophilic groups in the molecule, the oleophilic group comprising a hydrocarbon group containing at least eight carbon atoms, said chemical compound having good wetting and lubricating properties, being miscible with water and having the properties of penetrating through the natural greasy 70 layer on the skin and facilitating the soften-

ing of the hair when applied to the skin, the ingredients above mentioned being present in substantially the following proportions:

	Per cent
Oleaginous material	5-30
Chemical compound	1/2-5
Water	50-80

4. The product of claim 3 wherein the chemical compound is a member of the class consisting of oxygenated inorganic acid esters of aliphatic alcohols, having at least eight carbon atoms in the aliphatic chain, and salts thereof. 10

5. The product of claim 3 wherein the chemical compound is a member of the class consisting of sulphuric acid esters of aliphatic alcohols 15 having at least eight carbon atoms and salts thereof.

6. The product of claim 3 wherein the chemical compound is a sulphuric acid ester of lauryl alcohol. 20

7. A brushless shaving cream comprising a plastic emulsion of oleaginous material having a terminal carboxy group, and a chemical compound having both hydrophilic and oleophilic groups in the molecule and comprising a member of the class consisting of inorganic oxygenated acid esters of aliphatic alcohols having at least eight carbon atoms in the aliphatic chain, and salts thereof and water, the water being present in a major amount and the other ingredients being present in minor proportions. 25

8. A brushless shaving cream comprising a plastic emulsion of oleaginous material having a terminal carboxy group and water, and having included therein a proportion of a chemical compound containing both oleophilic and hydrophilic groups in the molecule and comprising a member of the class consisting of inorganic oxygenated acid esters of aliphatic alcohols, having at least eight carbon atoms in the aliphatic chain 40 and salts thereof.

9. A brushless shaving cream comprising a plastic emulsion of oleaginous material having a terminal carboxy group and water, and having included therein a proportion of a chemical compound containing both oleophilic and hydrophilic groups in the molecule and comprising a member of the class consisting of sulphuric acid esters of aliphatic alcohols with at least 45 eight carbon atoms and salts thereof. 50

10. A brushless shaving cream comprising a plastic emulsion of normally solid oleaginous material having a terminal carboxy group and water, and having included therein a proportion of a chemical compound of the class consisting of 55 sulphuric acid ester of oleyl alcohol and salts thereof.

11. A brushless shaving cream comprising a plastic emulsion of oleaginous and aqueous material, and having included therein a proportion 60 of a chemical compound having the general formula $R-O_{n-1}-Y$ wherein "R" is an oleophylic hydrocarbon radical with at least eight carbon atoms, "n" is one or two, and "Y" is a hydrophilic group comprising an oxygenated inorganic acid radical. 65

12. A brushless shaving cream comprising a plastic emulsion of oleaginous and aqueous material, and having included therein a proportion of a chemical compound containing both oleophilic and hydrophilic groups in the molecule and having the general formula $R-O_{n-1}-SO_3X$ 70 wherein "R" is an oleophylic hydrocarbon radical with at least eight carbon atoms, "n" is one or two, and "X" is a cation. 75

13. A brushless shaving cream comprising a plastic emulsion of a normally solid oleaginous material having a terminal carboxy group and aqueous material, and having included therein a proportion of a chemical compound containing both oleophilic and hydrophilic groups in the molecule and comprising a salt of an alkyl sulfonate, wherein the alkyl radical has at least eight carbon atoms.
14. A brushless shaving cream comprising a plastic emulsion of a normally solid oleaginous material having a terminal carboxy group and aqueous material, and having included therein a proportion of a salt of the sulphuric acid ester of cetyl alcohol.
15. A brushless shaving cream comprising a

plastic emulsion of oleaginous material having a terminal carboxy group, soap, and a chemical compound having oleophilic and hydrophilic groups in the molecule and comprising an inorganic oxygenated acid ester of an aliphatic alcohol having at least eight carbon atoms in the aliphatic chain, and water, the proportions of the ingredients being substantially as follows:

	Per cent	
Oleaginous material	5-30	10
Soap	2-10	
Ester	1/2- 5	
Water	50-80	

WOLF KRITCHEVSKY. 15
